UNITED STATES PATENT OFFICE

FRED L. MENELEY, OF GLENDALE, CALIFORNIA

CURTAIN FITTING MEANS

Application filed June 10, 1930. Serial No. 460,174.

This invention relates to improved means for hanging and supporting flexible material such as, curtains, draperies, and the like and rendering them conveniently adjustable along a supporting member such as bars, rods or the like.

An object of the invention is to provide an improved clip or hanger for use in conjunction with the curtain and its supporting bar, said hanger being so constructed as to be readily slideable along the bar but being effectively safeguarded against accidental displacement therefrom.

Another object of the invention is to provide a curtain hanging clip whereon is mounted, in an improved manner, an anti-friction roller which is adapted to travel smoothly along the supporting member and which is securely maintained in a proper operative relation to said member.

Another object of the invention is to provide curtain supporting means, which in conjunction with other improved features, will include a curtain having a novel hem along its upper edge so formed as to safeguard the curtain from wearing or becoming torn at the point or points where it is engaged by the supporting means.

Another object is to provide simple, and novel means for supporting a curtain so that when the curtain is in drawn position the supporting bar and associated parts will be concealed from view on one side of the drawn curtain.

Another object of the invention is to provide novel means whereby a flexible curtain may be supported by clips or hangers combined with the rail whereon they are mounted to form a very simple, inexpensive and novel means for supporting the same in such a manner that the curtain supporting elements are all located on but one side of the curtain, so that no hanging equipment will be visible from one side of the curtain, and a neater, more pleasing appearance of the curtain will therefore result.

The invention includes the parts and combinations of parts more particularly herein-after described and claimed.

A further object is to provide a novel cur-

tain supporting means which may be easily and quickly attached to and detached from the curtain that it is to support, as well as one which may be easily and quickly attached to and detached from its supporting rail.

A still further object is to provide a simple, novel curtain supporting means which may be effectively associated with a curtain to obtain the foregoing objects without sewing or otherwise fixedly securing the curtain to the supporting means.

Other objects, advantages and features of invention may appear from the accompanying drawings, the subjoined detail description and the appended claims.

The invention is illustrated, by way of example, in conjunction with a shower bath curtain but it is to be understood that its use is by no means confined to curtains of this character, as it may be adapted to support any flexible member.

Referring to the accompanying drawings, which illustrate what is at present deemed to be a preferred embodiment of the invention,

Figure 1 is a perspective view of a shower bath curtain partly drawn and showing the same supported by my novel invention. A corner of a bath room is illustrated to show one manner of practical adaptation of my invention.

Fig. 2 is an enlarged vertical cross section through the supporting means and the upper portion of the curtain, a fragment of which is more or less diagrammatically illustrated.

Fig. 3 is a broken side elevation including only a fragment of the curtain and rail illustrating the relative positions of the parts.

Fig. 4 is a detail plan view of one of the hangers or clips for supporting the curtain together with its anti-friction roller.

The curtain 7 may be of a rubber fabric or of any other material desired, being provided along its upper edge with a folded over part or hem 8 thus producing a pocket 9. The lower edge of the hem 8 is provided with an upwardly directed terminal portion 11 which underlies the body portion of the curtain 7, stitches 12 secure the free edge of the hem to the body portion of the curtain.

Spaced along the hem 8, near the lower edge thereof, is a series or plurality of apertures 15 the edge portions of which are reinforced in any desirable manner, as by the 5 eyelets or grommets 16.

The curtain is shown supported from a tubular rod or bar 20 which is rectangular in cross-section. This bar is preferably mounted on edge as shown in Fig. 2 so that its sides 10 will be vertical,

The curtain 7 is supported from the bar 20 by means of the series of hangers or clips 25 one of which is illustrated. Each of said hangers comprises a strip, wire or rod which 15 is bent into the general shape of a vertically compressed letter S, having a supporting loop 26 formed at one side of a middle run 25' of the wire that extends around the rail 20, and at its lower or free end terminates in an inwardly directed finger 27 which tends to prevent vertical displacement of the hanger from the rail 20 and thereby reduces to a minimum 20 accidental disengagement of the hanger from rail 20.

25 The other end portion of the hanger is provided with a curtain supporting loop 30 which provides an upstanding limb 31 that forms the curtain-engaging portion of the hanger. The loop 30 is adapted to be inserted 30 through an eyelet 16 in such a manner that the weight of the curtain at such point is supported at the eyelet and the limb 31 enters the pocket 9 and serves to maintain hem 8 in an upright position to conceal bar or rail 20 35 when the curtain is drawn. The hangers 25 are positioned along curtain 7 at any desired intervals so that the locations of arms 31 will adequately support the curtain.

It will be seen that each clip 25 is formed 40 of a single piece of wire and that at each side of its central run 25' a loop is provided, the open end of which is directed oppositely to its companion loop. The open end of the loop 26 may be slipped over the rail 20 to 45 mount the hanger on the rail 20 without removing the rail from its supporting members, and the loop 20 is sufficiently obstructed by the finger 27 to prevent the clip from being lifted off from or laterally displaced with 50 relation to said rail during operation of sliding the curtain along said rail either to open or drawn positions.

In mounting or removing my novel hanger on the rail 20 the loop 26 may be easily 55 sprung, as the same is made from wire, to permit installation or removal of the hanger from rail 20. A wheel or roller 40 is mounted on loop 26 to provide simple means for ease of operation when moving the curtain suspended by my novel hanger along rail 20.

A portion of the wire loop 26 is of sufficient length to form a bearing shaft for said roller 40, and in order to provide retaining means and centering means for said roller 40, the wire forming the loop is cut to provide 60

spaced projections or small lugs or ears 41 which maintain the roller between them and keep the roller in proper position.

In the drawings the curtain 7 is illustrated 70 as mounted for use as a shower-bath curtain in conjunction with a bath tub 45, said tub being located in a corner portion of the bath room A and the curtain rod or bar 20 being positioned to support the curtain along and over the two sides of the tub which are not 75 adjacent to the wall. This arrangement of tub, curtain, and curtain-supporting means is well suited to shower bath equipment because it provides for adjusting the curtain in such a manner that the curtain will keep 80 water from splashing onto the floor while a shower bath is being taken. However, it is understood that my novel curtain-fitting may be used either for curved bars 20 as shown or for straight bars without bend B 85 or for suspending any desirable material such as, drapes, cretonnes, etc., without departing from the spirit of my invention.

From the foregoing it will be seen that I 90 have provided a novel curtain-fitting in the form of a vertically compressed letter S in which the supporting loop extends on all 95 four sides of, and substantially enclosing the rectangular supporting bar or rail 20, and in which the curtain supporting loop extends above the rail 20 so that a curtain supported thereon will conceal the roller 40 and its underlying co-operating parts.

In hanging a curtain upon the supporting 100 bar 20, it will be apparent that the supporting bar 20 will not have to be removed from its supporting bearings as the hangers or 105 clips 25 are preferably first placed upon the supporting bar 20 by slipping the loop 26 over bar 20 and, if necessary, this loop may be easily sprung to accomplish such purpose. Then the curtain, which has been previously 110 formed with the hem 8 and the grommets or eyelets 16, is mounted upon the loop 30 of the hanger 25 by merely slipping the limb 31 of hanger 25 through the eyelet 16 so that the 115 limb 31 is received in the pocket 9 of hem 8. To remove the curtain, it will be apparent that one is only required to raise the curtain off from the limb 31 of supporting loop 30.

The ease of hanging a curtain on my novel 120 hanger and the ease with which the same may be removed for laundering purposes will at once be apparent to those skilled in the art, as no sewing or other fastening than above referred to is required to effectively support a curtain on my novel hanger so that the head of the curtain will extend above the supporting means to conceal the same when the curtain is drawn. Furthermore, the curtain, when supported on my hanger 25, will hang vertically with respect to its surface without the head extending forwardly or rearwardly with respect to the curtain surface.

I claim:

1. Curtain supporting means comprising in combination a curtain having a hem along its upper edge, there being apertures through 5 one face of said hem; clips each having an upwardly directed arm extending through an associated aperture and housed within said hem and adapted to support said hem in an upright position, each clip, also having an intermediate portion engaging the said apertured portion of the curtain to support said curtain thereon; and supporting means whereon each clip is mounted.

2. Curtain supporting means comprising in 15 combination a bar; a clip consisting of an elongated strip of material bent into the general shape of a vertically compressed letter **S**, said supporting bar being included within one loop of said clip and maintaining the terminal arm of the other loop of the clip in an upstanding position, and a curtain having a loop marginal portion which is adapted to be supported both by the terminal portion 20 of the last recited loop of the clip and by the bent portion thereof.

3. Curtain supporting means comprising in 25 combination a bar having a width considerably greater than its thickness; and a clip consisting of a rod bent into the general shape 30 of a vertically compressed letter **S**, the loop thus formed at one side of the mid-length of said rod extending around said rail, said loop terminating in a finger which prevents lateral displacement of said clip from said rail, the other end portion of said rod being adapted 35 to support a curtain.

4. Curtain supporting means comprising in 40 combination a bar having a width considerably greater than its thickness; a clip consisting of a rod bent into the general shape of a vertically compressed letter **S**, the loop thus formed at one side of the mid-length of said rod extending around said rail; said loop terminating in a finger which prevents lateral 45 displacement of said clip from said rail, the other end portion of said rod being adapted to support a curtain; and a roller mounted upon the middle portion of said clip and adapted to travel upon said bar.

5. A curtain hanger clip comprising bent 50 portions of wire, one of which portions is adapted to support a curtain and the other of which portions is adapted to retain said hanger clip in place upon a bar; and a roller 55 adapted to travel upon the bar, the wire forming a bearing shaft for said roller, said wire having a projection at each side of said roller to prevent relative sidewise movement of said roller on said wire.

6. Curtain hanging means comprising in 60 combination, a single wire bent into a clip having a central run and an open-ended loop at each side of said run; a bar of greater height than width mounted in an edgewise position over which one of said loops is placed

with its open end directed downwardly, the last recited loop being provided with a finger which sufficiently obstructs its open end to act as a keeper to keep said clip from being either laterally or vertically displaced from said rail, the loop at the other side of the central run of the clip being adapted to engage and support a curtain.

7. In curtain supporting means, the combination of a rectangular supporting bar and a curtain engaging clip comprising a rectangular supporting loop adapted to overlie the four sides of said bar and substantially encircle the same, and a curtain supporting loop 70 extending away from one corner of said first mentioned rectangular supporting loop and adapted to support a curtain thereon.

8. The combination of a curtain having a hem provided on one side with apertures; a supporting bar; and a clip slidably mounted 75 on said bar and having an upstanding finger detachably received in said aperture and hem and adapted to support said curtain so that said bar and clip will be concealed on one side of said curtain supported thereon.

9. In curtain supporting means, a clip 80 made of a single strip of wire bent into a substantially vertically compressed **S**-shape to form a bar engaging loop and a curtain supporting loop, said bar engaging loop having 85 its free end extended toward said curtain supporting loop to provide means to retain said clip on a supporting bar.

10. In curtain supporting means, a clip 90 made of a single strip of wire bent into a substantially vertically compressed **S**-shape to form a bar engaging loop and a curtain supporting loop, said bar engaging loop having 100 its free end extended toward said curtain supporting loop to provide means to retain said clip on a supporting bar; and a roller mounted 105 on said bar engaging loop.

11. In curtain supporting means, a clip 110 made of a single strip of wire bent into a substantially vertically compressed **S**-shape to form a bar engaging loop and a curtain supporting loop, said bar engaging loop having 115 its free end extended toward said curtain supporting loop to provide means to retain said clip on a supporting bar; a roller mounted on said bar engaging loop; and means on said wire to prevent relative lateral movement of said roller on said wire clip.

12. In curtain supporting means, a clip 120 made of a single strip of wire bent into a substantially vertically compressed **S**-shape to form a bar engaging loop and a curtain supporting loop, said bar engaging loop having 125 its free end extended toward said curtain supporting loop to provide means to retain said clip on a supporting bar; said bar engaging loop and retaining means forming a substantial rectangular shaped member.

13. In curtain supporting means, the combination of a curtain having on one side a 130

- series of apertures; a rectangular supporting bar; a clip having a loop extending over said bar and slidable therealong and detachable therefrom; and a curtain engaging finger extending upwardly and away from said loop and supporting bar and adapted to be detachably received in said apertures and maintain one edge of said curtain at a height above said bar and clip.
- 10 14. In curtain supporting means, a clip comprising a wire bent to form a middle run and a bar supporting loop extending from one end of said middle run and a curtain supporting loop extending from the other end of
- 15 said middle run, said loops opening at opposite ends of said middle run, the free end of said bar supporting loop extending toward said curtain supporting loop; and a roller mounted on said bar supporting loop and
- 20 adapted to rotatably engage a supporting bar.

In testimony whereof, I have hereunto set my hand at New York, N. Y., this 9th day of June, 1930.

FRED L. MENELEY.
